FASTENING MEANS FOR TOOL HANDLES

Morgan A. Nyberg, Milwaukee, Wis.

Application November 18, 1935, Serial No. 50,349

4 Claims. (Cl. 306—33)

This invention relates to tools, especially to wooden handled tools and refers particularly to holders for securing the handles in the tool heads.

5 In the past, holders for wooden handled tools have been so constructed and applied that parts of them protruded out beyond the top of the tool head. In claw hammers, this was very objectionable, for if a nail was to be withdrawn 10 from a smoothly finished surface, the protruding portion of the holding device would scratch and leave deep scars in the surface of the same.

The present invention thus has as one of its 15 objects to provide a locking or holding device for securing handles in tool heads, which is so constructed that no portion thereof protrudes from the top of the tool head.

Another object of this invention is to provide 20 a locking or holding device that affords a simple means of securement between the head of the tool and a wooden handle, and which also becomes effective automatically upon assembling of the parts.

A further object of this invention is to provide 25 a holder for securing a wooden handle in the socket of a tool head which has parts thereof adapted to automatically snap into notches in the handle and the tool head as the parts are assembled.

30 With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates two 40 complete examples of the physical embodiment of the invention constructed according to the best modes so far devised for the practical application of the principles thereof, and in which:

Figure 1 is a side view of a hammer with parts 45 broken away and in section to illustrate one application of this invention;

Figure 2 is a view in section taken on the plane of the line 2—2 in Figure 1;

Figure 3 is a perspective view of the holding 50 device per se;

Figure 4 is a fragmentary section view showing a simple manner of notching the socket wall of the tool head;

Figure 5 is a view in side elevation of an axe to 55 show a modified embodiment of the invention;

Figure 6 is a view in section taken on the plane of the line 6—6 in Figure 5.

Referring now particularly to the accompanying drawing, in which like numerals indicate like parts, the numeral 5 represents a tool, which in 5 the present instance, is illustrated as a conventional claw hammer having a handle receiving socket 6 in its medial portion, and a wooden handle 7 having one end portion 8 inserted into the socket.

In the past, various means have been provided 10 for securing the handle in the socket, the most common being a wedge driven into the handle end disposed within the socket so as to spread the same into intimate contact with the out- 15 wardly flared diverging walls of the socket.

This manner of securing the handle in the 20 socket is objectionable due as in use the wedge soon becomes loose and permits detachment of the tool head from the handle.

To overcome this objection, holding devices 25 were designed which effected some sort of interlocking connection between the tool and the handle, but all past expedients of this type have been complicated and inadequate. In many instances the tool head had to be of special construction with parallel walls in its socket. Also, holding devices heretofore proposed often had parts thereof protruding from the top of the tool head which, as noted hereinbefore is de- 30 cidedly objectionable.

The holding device 9 of this invention, on the other hand, is extremely simple and effective and may be used either with or without the wedge. However when it is used with the wedge 35 it is applicable to any type of tool head and does not require the socket walls to be parallel. As best illustrated in Figure 3, this holding device consists of a flat strip of metal, preferably spring steel, of a length substantially shorter 40 than that of the socket 6. One end of the strip is bent laterally to form a flange 10 adapted to engage the inner end of the tool socket as illustrated in Figure 1. The opposite end of the holding device is bent slightly away from 45 the socket wall as at 11, and the edge thereof engages a shoulder 12 formed in the handle by cutting a notch or recess 13 in its side when the parts are assembled.

At its medial portion, and near the flanged 50 end 10, the holding device has a spring tongue 14 struck therefrom. The spring tongue projects in a direction opposite to that of the bent end 11 and engages a shoulder in the socket wall formed by drilling or grinding a notch 15 into 55

the socket wall (see Figure 4), so that when the handle provided with the holding device is assembled with the tool the tool head will be securely held against displacement. While it is desirable to provide two holding devices, one opposite the other, it is obvious that a single holding device may be used with satisfactory results.

In assembling, the holding devices are first placed in the tool head socket with their tongues 14 engaging in the notches 15 and their flanged ends 16 overlying the inner end of the socket. So positioned, the holding devices are held against endwise movement with respect to the tool unit 15 with their spring ends 11 curving inwardly a substantial distance into the hollow of the socket.

With the holding devices so located, the handle, after being filed or cut to fit the socket and having the recesses 13 formed therein, is inserted and driven into the socket in the conventional manner. As the handle is driven into the socket, the spring ends 11 of the holding devices are deflected and snap into operative positions engaging the shoulders 12 upon alignment 25 of the shoulders therewith.

While in the embodiment shown, the handle end portion has but one set of shoulders 12, it will be readily apparent that a number of such shoulders may be provided at spaced intervals along the length of the handle portion so that the handle need not be driven into the socket to just one position.

As tool handles generally have a tapered socket, a wedge 11 has been provided to force 35 the walls of the outer end of the handle into intimate contact with the socket walls.

While the holding device of this invention is particularly applicable to claw hammers in that no parts thereof protrude from the top of the hammer head, it is not restricted to this one use, and in Figures 5 and 6 a slightly modified embodiment of the invention is illustrated applied to a conventional axe.

In this embodiment of the invention the holder 45 18 has a body portion 19 curved in cross section to fit a correspondingly curved wall of a socket in a tool such as an axe. In other respects the holder 18 and its manner of use is the same as has been described.

From the foregoing description taken in connection with the accompanying drawing it will be readily apparent to those skilled in the art that this invention affords a simple and effective means for securing tool heads to wooden handles, 55 which leaves the top surface of the tool heads free from any projections that might mar or scratch surfaces to which they may be applied, and that application of the same is easily effected.

What I claim as my invention is:

60 1. In a tool of the character described, a head having a socket provided with a notch in one wall thereof, a handle having an end portion disposed in the socket, a shoulder on said handle end portion, a holding device between said wall of the socket and the adjacent surface of the handle end portion and having a part engaging said shoulder on the handle, a flange on the holding device engaging the inner end of the head to prevent outward movement of the holding device with respect to the tool head, and a spring tongue projecting from the holding device into the notch in said wall of the socket to prevent movement of the holding device with respect to the tool head in the opposite direction.

2. In a tool of the character described, a head having a socket therethrough with one end of the socket opening to the outer face of the head and its other end opening to the inner face of the head, one wall of the socket having a shoulder facing the outer face of the head, a handle having an end portion disposed in the socket with the end thereof flush with the outer face of the head so as not to protrude therefrom, a shoulder on said end portion of the handle facing the inner face of the tool head, a holding device between said wall of the socket and the adjacent surface of the handle end portion with a part thereof engaging the shoulder on the handle end portion and another part engaging the shoulder in said wall of the socket, and a flange carried by the holding device and engaging the inner face of the tool, said flange coating with the engagement between the holding device and said shoulders to secure the handle against removal from the tool head without the necessity for protrusions from the outer face of the tool head.

3. A holding device for securing handles to tool heads comprising a strip of metal having a yieldable end portion bent away from the longitudinal axis of the strip to engage down into a recess in the handle to hold the strip against longitudinal movement in one direction with respect to the handle, a spring tongue struck from the strip and projecting in the opposite direction for engagement with a shoulder on the tool head to hold the strip against longitudinal movement in the same direction with respect to the tool head, and a flange on the end of the strip opposite said bent end and engageable with the inner face of the tool head to hold the strip against longitudinal movement in the opposite direction with respect to the tool head.

4. A holding device of the character described comprising a strip of metal curved in transverse cross section and having one end portion bent inwardly to provide an abrupt sharply defined edge portion engageable with a shoulder in the handle of a tool, a spring tongue projecting outwardly from the outer curved surface of the strip for engagement with a shoulder in the head of a tool, and a flange on the opposite end of the strip extending perpendicularly from the outer curved surface of the strip to overlie and engage one face of a tool head.

MORGAN A. NYBERG.
